CLAIM

The ornamental design for a dispenser for film packages or similar articles, as shown and described.

DESCRIPTION

FIG. 1 is a top, front, and right side perspective view of a dispenser for film packages or similar articles showing my new design;

FIG. 2 is an enlarged front elevational view thereof;

FIG. 3 is an enlarged rear elevational view thereof;

FIG. 4 is an enlarged bottom plan view thereof;

FIG. 5 is an enlarged top plan view thereof;

FIG. 6 is an enlarged right side elevational view thereof; and,

FIG. 7 is an enlarged left side elevational view thereof. The article is shown broken-away in some of the views for convenience of illustration.
